UNITED STATES PATENT OFFICE.

THOMAS SIMMONS HOMANS, OF BROOKLYN, NEW YORK, ASSIGNOR TO MERGENTHALER LINOTYPE COMPANY, A CORPORATION OF NEW YORK.

LINOTYPE-MACHINE.

No. 890,425.

Specification of Letters Patent.

Patented June 9, 1908.

Application filed March 24, 1908. Serial No. 422,935.

To all whom it may concern:

Be it known that I, THOMAS SIMMONS HOMANS, of borough of Brooklyn, county of Kings, and State of New York, have invented 5 a new and useful Improvement in Linotype-Machines, of which the following is a specification.

My invention relates to improved mechanism supporting and adjusting the knives 10 used in Mergenthaler line-casting machines, and kindred machines, for trimming the side faces of the slugs or printing bars as they are ejected from the mold in which they are cast. In this class of machines, it is necessary 15 that the slugs shall be trimmed very accurately to a predetermined thickness, and that their opposite faces shall be exactly parallel. To this end, it is common to employ two stationary knives, one of which is adjustable toward and from the other, in order to vary the 20 distance between them according to the thickness of the slugs required.

Owing to the various conditions which are encountered in practice, it has been found 25 extremely difficult to effect the accurate adjustment of the knives and hold them in operative position with the required rigidity.

In place of the ordinary means, I make use 30 of a sliding guided support to which the movable knife is firmly secured, and I combine with this sliding support a screw provided with right and left threads, one of which is seated in the knife-supporting plate, and the other in a stationary nut, so that when the 35 screw is turned, the sliding knife support is caused to move in relation to the screw, and the screw also, caused to move bodily in an endwise direction. I combine with this screw an operating handle and means for 40 locking the same in definite positions, and I provide springs tending to prevent lost motion of the parts, and to aid in the adjustment of the movable knife on its support.

In the drawings,—Figure 1 is a horizontal 45 section through my improved trimming mechanism on the line 1—1 of Figs. 2, 3 and 4. Fig. 2 is an end elevation of the same, looking in the direction of the arrow 2 in Fig. 1. Fig. 3 is a face view in the direction of 50 the arrow 3 in Fig. 1. Fig. 4 is a cross-section on the line 4—4 of Figs. 1 and 3. Fig. 5 is a perspective view of the knife-supporting slide. Fig. 6 is a cross section on line 6—6,

Fig. 3, showing the manner in which the movable knife is adjustably secured to its carrying slide. 55

Referring to the drawings A, A' represent a rigid frame or block intended to be bolted to the main-frame of the machine and support the various operating parts of the trimming mechanism. It may be made of any suitable form, but is preferably constructed as shown, of two parts united by bolts *a* and *a'* having between them a throat or passage *a'* through which the slugs are ejected. 60

B is a stationary knife secured to the frame by bolts *b*.

C is a movable knife slotted to receive screws *k*, by which it is secured firmly to the supporting slide *D*, which is screwed firmly 70 to and in effect forms a part of a cylindrical guiding member *E* arranged to slide horizontally in an opening in the frame *A'*.

The member *E*, which may be made of other than a circular form in cross-section, is 75 snugly fitted in its seat so that it may slide endwise, and is relied upon as the principal means for guiding the plate *D* and the knife thereon. This guide is preferably provided in one side with a longitudinal groove to receive a corresponding rib on the plate, as clearly shown in Figs. 1 and 4, this connection preventing any possibility of change in the relation between the guide and the plate. It will be observed that the axis of this guide 80 *E* is at right angles to the cutting edge of the knife, so that it serves to keep the knife *C* in exact parallelism with the opposing knife *B*.

The face of the supporting plate *D* is flattened and seated snugly against the frame *A'* 90 to assist in guiding and giving rigidity to the parts.

The forward and backward movement of the plate *D* to change the distance between the knives, is effected by the screw *F*, having 95 at opposite ends the reversely inclined threads *f* and *f'*.

The thread *f* is seated in a projection on the plate *D*, while the thread *f'* is seated in a nut or enlargement *a* formed on the fixed frame, 100 so that when the screw is turned in either direction, it is shifted axially and bodily through the nut *a*, while at the same time it causes the plate *D* to move forward or backward upon the screw.

The screw is operated and controlled to ad- 105

vance and retract the knife definite distances by a hand-lever G secured to its end. This lever is preferably made in the form of an elastic blade rigidly secured to the end of the 5 screw and provided with a handle g having a toothed plate g' to engage studs a² on the periphery of a sector plate a² formed upon or secured rigidly to the frame.

Normally the plate engages one of the 10 studs, as shown in Figs. 1 and 5, thereby holding the lever and the knife securely in position. When adjustment of the knife is required, the lever is pressed laterally in order to disengage the plate g', after which the 15 lever is turned till the knife is in the required position, and then permitted to engage another stud. Any other suitable means may be employed for locking the lever in the various positions.

20 In practice, the sector plate is graduated and the screws so proportioned that the movement of the lever from one stud to the next will change the distance between the knives one point,—a point being the 25 printer's unit of measure.

In order to prevent accidental disengagement of the lever, I propose to provide any suitable locking device, for example, a screw g⁴ seated transversely in the lever and adapted to be screwed against the outer face of the 30 sector plate.

In order to permit the very slight variations in the thickness of the slugs, I propose to provide the lever with a scale or vernier to 35 be read in connection with marks on the studs or on the sector plate. The preferred form of this device is shown in Figs. 1 and 2 in which I represents a finger pivoted in a slot in the hand-lever, and provided with 40 graduations at one end. It stands normally within the lever and in an inoperative position, as shown in Fig. 2, but may be turned outward at will, as shown in dotted lines, in order that its graduations may be read in 45 connection with the studs or the plate.

In order to prevent play or lost motion between the thread and the other parts, I recommend the employment of one or more springs H seated at one end in the frame and 50 bearing at the opposite end against the rear face of the movable knife C. These springs insure the exact adjustment of the knife when the screw is turned in either direction. They also serve to urge the knife C forward 55 in relation to its supporting plate D in opposition to the influence of the screws J, which are passed through a flange on the plate D into the back of the knife C for the purpose of adjusting the knife forward and backward 60 on the supporting plate D. These screws, located at opposite ends of the knife, have the effect, when turned in the proper direction, of drawing the knife backward in relation to the plate D and away from the opposi-

ing knife B. By turning one or both screws, 65 the knife may be adjusted upon the plate D until its edge is in exact parallelism with the knife B. After being thus adjusted, the knife is secured immovably in place upon the plate by screws K which connect them. 70

It is usual in this class of machines to employ in connection with the movable knife, a plate L, pushed forward by a spring M, to assist in confining and guiding the slugs of different thicknesses as they are delivered 75 between and beyond the knives. It is proposed to insert one edge of this plate in grooves in the knife C, as usual, and to attach the spring M to the end of the guiding member E. 80

The plate D and its guide E are made in separate parts in order to facilitate their manufacture, but it is obvious that the guide may be made integral with the plate if desired, and of any suitable form in cross-sec- 85 tion.

In operating my device, it is only necessary to move the lever to one side in order to unlock it from the sector plate, and then swing it in one direction or the other until it 90 is opposite that stud which corresponds to the thickness of the required slug, whereupon the lever is permitted to reengage the plate.

Having thus described my invention, I claim and desire to secure by Letters Pat- 95 ent,—

1. In combination with a supporting-frame, a knife-bearing plate guided therein, a right and left-hand screw connecting said parts, and means for turning the screw to 100 and securing it in definite positions.

2. In combination with a frame A, A', the plate D provided with the guide E, the knife C secured to said plate, the right and left-hand screw connecting the frame and plate, 105 the lever attached to the screw and means for locking the lever in predetermined positions.

3. In combination with a frame provided with a sector plate and the knife-bearing 110 plate guided therein, the right and left-hand screw, the spring lever attached to the screw and adapted to interlock with the sector.

4. In combination with a frame, a sliding support for the knife mounted thereon, a 115 screw for moving the knife-support, a lever for turning the screw, a stationary plate to which the lever locks, and a graduated plate on the lever.

5. In combination with a sliding member 120 supporting the knife and the screw for moving said member, the spring-arm or lever attached to the screw and provided with a toothed plate, and a sector plate having studs or teeth to interlock with the plate on 125 the lever.

6. In combination, the frame, the plate D guided thereon, the knife C mounted on the

plate, means for adjusting the plate, a spring, H, acting against the back of the knife, and screws, J, connecting the plate and knife and acting in opposition to the spring; whereby adjustment of the knife upon the plate is facilitated.

In testimony whereof I have hereunto set

my hand this thirteenth day of March, 1908, in the presence of two attesting witnesses.

THOMAS SIMMONS HOMANS.
